MULTIANGULAR REFLECTOR SIGN

Joseph C. De Marco, St. Paul, Minn.

Application September 4, 1943, Serial No. 501,220

18 Claims. (Cl. 40—76)

1

My invention relates to an improvement in multi-angular signs, wherein it is desired to provide a sign which produces a different display from various positions with relation thereto.

An object of the present invention lies in the provision of a sign formed of a series of multi-angular elements having directionally operable reflector buttons, or the like, associated therewith. These reflector buttons are so mounted on the multi-angular supporting units that the sign provides one display when viewing the same from one angle, and provides one or more different displays when viewing the sign from one or more different angles with respect thereto.

An object of the present invention lies in the provision of a sign embodying a series of multi-angular supporting units each provided with a plurality of supporting surfaces. A support is provided on each multi-angular supporting unit for supporting reflector elements visible from one position in front of the sign. One or more other supporting surfaces are likewise provided on each supporting element arranged to support reflector elements visible from one or more angles with respect to the sign. As a result two or more displays are provided from different angles with respect to the supporting units.

A further feature of the present invention lies in the fact that the supporting units may be rotatably mounted to move in unison. As a result a constantly changing display may be provided for a person standing in front of the sign and at a fixed angle with relation thereto.

A further feature of the present invention lies in the fact that one type of sign may be provided to be visible by day light, while another type of sign may be visible at night. For example, each of the rotatably mounted multi-angular supporting units may be provided with a flat display surface on which a suitable display or advertisement may be printed to be visible in the day time, while on the opposite surfaces of the units a series of reflecting elements may be mounted. Accordingly during the day the flat painted or otherwise decorated surfaces may be turned forwardly so that a painted advertisement may be visible to those looking at the sign. However, during the hours of darkness the reverse side of the supporting elements may be displayed so that different displays will be reflected from different angles with respect to the supporting elements.

A further feature of the invention lies in the fact that illumination of the reflecting sign may depend either upon movable lights such as the headlights of approaching vehicles, or the various

2

reflecting elements may be illuminated by different lights mounted at desired angles with respect to the sign to provide a constant illumination of the reflecting elements.

5 A feature of the present invention lies in the fact that an animated sign may be produced without the use of any moving parts, if it is so desired. For example, a picture or display may be provided in one position of the sign, the reflecting elements 10 forming the same being visible from an extreme angle with respect to the sign. A second picture or position of the picture may be provided on a second angular surface of each of a number of supporting elements, the reflecting elements 15 forming the same being visible from a somewhat different angle. Similarly a series of displays can be displayed to a person travelling along an angular path relative to the sign, and each successive display may, if desired, be related to the previous 20 display. As a result the illusion of an animated display or a moving picture may be obtained without requiring any moving of the parts of the sign.

A further feature of my invention lies in the fact that the reflector elements forming my sign 25 may be so arranged as to be visible to persons travelling along paths at different levels relative to the sign. Thus my sign may, if desired, provide one display for persons traveling on a level somewhat above the level of the sign, a second display to persons located on approximately the plane of 30 the sign, and a third display to persons located somewhat below the level of the sign.

A further feature of the present invention lies 35 in the fact that in preferred form the reflector units forming the display may be readily changed from time to time so that the display may be varied occasionally to change the nature of the display.

These and other objects and novel features of 40 my invention will be more clearly and fully set forth in the following specification and claims.

In the drawings forming a part of my specification:

Figure 1 is a perspective view of a sign showing 45 the display as it would appear from one angle with respect thereto.

Figure 2 is a diagrammatic top plan view of 50 the sign illustrated in Figure 1.

Figure 3 is a vertical section through the sign 55 showing the manner in which the parts thereof are constructed.

Figure 4 is a top plan view of a series of consecutive supporting units showing the relationship theretwixen.

Figure 5 is a perspective view illustrating the

manner in which the supporting units are constructed.

Figure 6 is a cross-sectional view through one of the reflector element supporting channels illustrating the construction thereof.

Figure 7 is a diagrammatic plan view of a sign illustrating the different positions from which the sign should be viewed to note the various displays thereupon.

Figure 8 is a top plan view of a pair of reflector supporting units showing the relationship therebetween.

Figure 9 is a top plan view of a series of reflector supporting units of a slightly different construction from those shown in Figures 4 and 8 of the drawings.

Figure 10 is a view similar to Figures 4 and 8, but showing another modified form of construction.

Figure 11 is a top plan view of a reflector supporting unit having more than three angular surfaces thereupon on which supporting elements are to be mounted.

Figure 12 is a diagrammatic top plan view of a sign constructed of supporting units such as are illustrated in Figure 11, and showing the various positions in front of the sign from which the various displays may be best viewed.

Figure 13 is a top plan view of another modified form of reflector supporting units.

Figure 14 is a front elevational view of a section of a sign formed of reflector element supporting units of a somewhat different type from those previously disclosed.

Figure 15 is a view similar to Figure 14 showing the reflector units in a somewhat different relationship.

Figure 16 is an enlarged view of one of the reflector elements which may be used in the sign illustrated in Figures 14 or 15.

Figure 17 is a modified form of construction of the reflector element illustrated in Figure 16.

Figure 18 is a diagrammatic plan view of a modified form of rotating sign construction.

Figure 19 is a top plan view of a portion of a modified form of sign.

Figure 20 is a side elevational view of a portion of the sign illustrated in Figure 19.

Figure 21 is a perspective view of a sign panel, illustrating another form of sign construction.

Figure 22 is a vertical section through the sign illustrated in Figure 21 showing the arrangement of reflector supports thereupon.

The sign A, illustrated in Figures 1 through 7 of the drawings, comprises a rectangular frame 10 including spaced parallel horizontally extending T-bars 11 and 12 and vertically extending connecting strips or elements 13 and 14. As best illustrated in Figures 2 and 3 of the drawings the series of reflector units supports B are mounted on vertical axes between the upper and lower frame elements 11 and 12. The elements B are mounted on a single shaft 15 extending vertically through the element, or may be mounted on aligned stub shafts projecting from the ends of each supporting unit. A ball bearing 16 encircles the upwardly projecting shaft portion 15 and rotatably supports this shaft portion in the frame element 11. A channel bearing 17 rotatably supports the lower projecting shaft end 16 upon the transverse frame element 12. Collars 19 and 20 respectively are provided adjacent the bearings 16 and 17 so as to hold the supporting elements B from vertical movement.

The worm wheel 21 is provided on the lower projecting shaft portion 15 and is arranged for engagement with a worm gear 22 mounted on a transversely extending shaft 23. The shaft 23 is supported in suitable bearings 24 and is rotated by any desired means, such as by the motor 25. Upon rotation of the motor 25 the supporting units B may be caused to rotate in unison through any desired degree of rotation.

Each of the reflector element supporting units B are constructed as best illustrated in Figures 4 and 5 of the drawings. The rear surface 26 of each supporting element B is flat from side to side. Projecting forwardly from the rear flat surface I provide a pair of converging inclined supporting surfaces 27 and 29 which are connected by a flat face 30 substantially parallel to the flat rear surface 26. A similar substantially parallel flat surface 31 is provided between the inclined surface 29 and the adjacent edge of the supporting unit. The two parallel surfaces 30 and 31 are arranged to support substantially parallelly arranged reflector units, while the surfaces 27 and 29 may be viewed one from one side of a line bisecting a sign and normal thereto, and the other on the other side of this line.

In order to support readily changeable reflector elements I provide ears 32 extending from the upper and lower ends of the supporting units B adjacent each surface thereof. In other words, a pair of opposed ears 32 are provided at opposite ends of the surface 27. A second pair of ears is provided at opposite ends of the surface 29. Similar pairs of ears 32 are provided at opposite ends of the surfaces 30 and 31. These pairs of ears 32 are arranged to pivotally support a channel 33 having aligned stub shafts 34 projecting from opposite ends thereof. Each channel 33 is provided with a base 38 and inwardly tapering side walls 35 so arranged as to retain a wedge shaped body slidably positioned in the same.

Each of the reflector elements 36 is provided with a wedge shaped supporting body 37 secured to the rear surface thereof. This wedge shaped body 37 is arranged to slide vertically in the channel 33. The various reflector elements 36 are held in adjusted relation by means of a clamping bar 39 mounted within the channel 33 rearwardly of the wedge shaped bodies 37. Set screws, such as 40, extend through the base 38 of the channel 33 and press against the bar 39, thus clamping this bar 39 against the base of the wedge shaped bodies 37, thus wedging these bodies in the channel 33. Thus the reflector elements 36 may be held in any desired adjusted relation by means of the clamping bar 39.

From an examination of Figure 7 of the drawings it will be obvious that the sign is to be arranged so that all of the reflecting elements on corresponding surfaces of the supporting units will be visible from a predetermined location. For example, if the sign is viewed from the point 41, illustrated in Figure 7 of the drawings, it is desirable that all of the reflectors 36, supported on the surfaces 30 and 31 of the supporting units be positioned at right angles to a line of vision from the point 41. This arrangement may be accomplished by adjusting the angular relation of the channels 33 with respect to the surfaces adjacent which they are mounted. For example, in order to adjust the angularity of the channel 33 mounted on the surface 30, pairs of adjusting bolts 42 and 43 are arranged in vertically spaced relation throughout the height of the

supporting units. These adjusting bolts 42 and 43 which may be accessible through small openings such as 44 in the rear surface 26 of the supporting units may hold the channel 33 in proper angular relationship with respect to the surface 30 so that the reflector units will be directly at right angles to a line drawn from the point 41. In order to adjust the channels 33 in one direction the bolts 43 are loosened and the bolts 42 are tightened. Similarly to adjust the channels in opposite direction the bolts 42 are loosened and the bolts 43 are tightened. Similar adjusting bolts are provided for each channel 33 so that the position of all of the various channels may be regulated.

When the sign A is viewed from the point 45, illustrated in Figure 7 of the drawings, only those reflectors mounted adjacent the supporting surfaces 27 will be visible. The channels 33 mounted adjacent the surfaces 27 may be adjusted in their angularity so that the reflecting elements supported will all be maintained at right angles to a line from the point 45.

Similarly the reflecting elements mounted in the channels 33 adjacent the surfaces 29 of the supporting units may be adjusted in angularity so as to all be at right angles to a line drawn from the point 46 shown in Figure 7. Thus at the point 41 one display will be visible. From the point 45 a second display will be visible. From point 46 a third display will be visible. An animated sign may thus be produced without the necessity of moving parts.

The various reflector elements may be illuminated by the headlights of vehicles travelling by the sign, or by any other suitable means. If a constant display of the reflector elements is desired, illuminating means such as the spot lights or floodlights 47 may be provided directed against the reflector elements on each angle of the sign. Thus the sign would be displayed to a pedestrian passing the same, as well as to a vehicle which might furnish its own source of light.

In place of the supporting unit construction B, illustrated in Figures 4 and 5 of the drawings, supporting units C, illustrated in Figure 8 of the drawings, may be used. These units which are illustrated only diagrammatically are provided with a flat rear surface 49 and a parallel front surface 50. Inclined side surfaces 51 and 52 are likewise provided similar to the inclined surfaces 27 and 28. This construction differs only from the previously described construction in that the surfaces 31 and the reflector elements mounted thereupon are eliminated in the construction shown in Figure 8. Each of the surfaces 50, 51, and 52 are provided with channels similar to the channels 33 in which the reflector elements 36 are supported. In this construction the parallel surfaces 50 are somewhat wider apart than in the previously described construction, as no intermediate parallel surfaces 31 are provided between the inclined surfaces. This construction, however, has the advantage of positioning the inclined surfaces more closely together due to the elimination of the surfaces 31. The supporting units C may be mounted similarly to the supporting units B.

The sign A is so arranged that during daylight the flat surfaces 26 of the various supporting units B may be exposed. These flat surfaces 26 may be painted or otherwise decorated to provide a sign visible by daylight.

During the darkness hours the opposite sur-

face of the display units are exposed. At twilight, either automatically or mechanically controlled means actuate the motor 25 to rotate units B through one-half of one revolution. The reflector bearing surfaces are thus exposed and a series of different signs may be viewed from different angles. At approximately daylight the motor 25 is again actuated to rotate the supporting units B into reverse position with the flat surfaces 26 thereof exposed.

In Figure 9 of the drawings I disclose diagrammatically another method of compensating for the angularity of the line of vision toward the various reflector elements forming the sign.

As illustrated in Figure 9, the central portion of the sign is formed of supporting units 53 having their forward surfaces 54 substantially parallel to the rear flat surfaces 55, and having their display surfaces 56 and 57 at similar angles with respect to the front and rear surfaces 54 and 55. Near the left hand end of the sign, however, the forward surface 59 of the supporting unit 60 is not parallel to the rear surface 61 thereof so that the reflector elements 62 mounted in the fixed channel 63 thereupon will reflect light toward a point in front of the center of the sign. Similarly the forward surface 64 of the supporting units 65 at the right hand end of the sign are not parallel to the rear surfaces 66 of these units, but rather are at an angle thereto so that the reflector units 67 mounted in the fixed channel 68 on the surface 64 will direct light toward a point forwardly of the center of the sign. As a result a person standing directly in front of the center of the sign will see the entire display perfectly as all of the reflector units on the front surfaces of the various supporting units are perpendicular to his line of vision.

As will be noted in Figure 9 of the drawings the angle of the surface 70 of the supporting unit 60 with respect to the rear surface 61 is somewhat greater than the angle between the surface 57 and the rear surface 55 of the supporting unit 53. Likewise the angle between the surface 71 and the rear surface 66 of the supporting unit 65 is somewhat less than the angle between the surface 55 and the surface 57 of the supporting unit 53. Accordingly reflectors mounted in fixed relation to the surfaces 57, 70, and 71 are all at right angles to the line of vision from a common point forwardly and to the right of the sign. As may also be noted from Figure 9 of the drawings the angle between the surfaces 72 and 61 of the supporting unit 60 is somewhat less than the angle between the surfaces 55 and 56 of the supporting unit 53. This latter angle is somewhat smaller than the angle between the surface 73 and the rear surface 66 of the supporting unit 65. As a result the reflector units mounted in fixed relation to the surfaces 56, 72, and 73 are all perpendicular to a line of vision from a predetermined fixed point forwardly and to the left of the sign.

Thus in effect, in place of adjusting the angularity of the individual channels 33 with respect to the supporting units B, the shape of the supporting units themselves may be varied so that the reflector units mounted in fixed relation thereto will all be perpendicular to lines of vision from certain fixed points.

In Figure 11 of the drawings I disclose a modified form of construction in which the supporting units D are provided with a multiplicity of supporting surfaces so that more than three reflector unit supporting channels may be sup-

ported thereby. In the construction shown in Figure 11 of the drawings the supporting units D are provided with a flat rear surface 74 and a curved or multi-faced forward surface 75. Five sets of supporting brackets or tongues 78 are provided, each of which support a channel 33, identical to that previously illustrated. Each of the channels 33 is arranged to support reflecting elements 36 which are capable of reflecting light to a person standing in predetermined relation relative to the sign E, as illustrated in Figure 12.

It will be noted that a person standing at the point 77 in Figure 12 will see light reflected from the reflector elements 36 mounted at one extreme side of each supporting unit D. A person standing at the point 79 will see light reflected from the reflector elements mounted in the next adjacent channel. A person standing directly forwardly of the sign at the point 80 will see light reflected from the centrally mounted reflector elements 36. Persons standing at the points 81 and 82 will see light reflected respectively from the remaining two sets of the reflecting elements. Thus to a person moving past the sign and viewing the same from various angles with relation thereto, they will see what might amount to an animated sign and as the various displays show somewhat similar figures in slightly different positions, an effect similar to that of a moving picture may be obtained. The reflecting elements may be illuminated either by the lights of passing vehicles or by fixed spot lights or floodlights, such as the lights 83 arranged to illuminate each set of reflector elements.

The reflector elements are preferably directional so that only one display will be seen at a time by a person viewing the same. In certain constructions and more particularly in those constructions in which several series of angularly arranged rows of reflector buttons are provided in close proximity, it is sometimes desirable to provide shields encircling the reflector elements and projecting therefrom so as to render the reflector elements definitely directional. These shields may or may not be used.

In Figure 10 of the drawings I disclose a construction very similar to the construction shown in Figure 8 of the drawings. The supporting elements F, illustrated in Figure 10 of the drawings, are shaped similarly to the supporting elements C. These supporting elements F include a flat front surface 84 and opposed inclined surfaces 85 and 86. Channels are supported on the surfaces 85 and 86 in any suitable way so as to support reflector elements such as 36. However, the front surface 84 is merely painted with a suitable display so that in daylight an advertising sign is provided without reversing the position of the various supporting elements. In other words, the construction shown in Figure 10 is similar to that shown in Figure 8, with the exception that the reflector elements and the supporting channels are omitted on the front surfaces 84, and a painted or decorated display is provided thereupon, visible in daylight hours.

In Figure 13 of the drawings, I disclose another modified form of reflector supporting element, illustrated in general by the letter G. These supporting elements G are in the form of hexagonal posts 87 provided with shafts 89 projecting therefrom so that the supporting elements may be rotatably supported in a manner similar to the method of supporting the units B. Six channels 90, similar or identical to the channels

33, are angularly spaced about the posts 87 and are secured thereto. Each of these channels 90 support reflecting elements 91 similar or identical to the reflecting elements 36. This light will be reflected from six different angles with respect to the axis of the supporting units G.

This type of construction is capable of numerous uses. In the first place, a series of supporting units G of the type illustrated, may be mounted in a sign which may be seen from both sides. Thus the sign may be mounted in the parkway between two parallel highways, or may be mounted at right angles to a highway for vision from opposite directions. The supporting units may either be stationary in their position, or may rotate in unison to provide an everchanging display to a person viewing the same.

Where a sign is so situated as to be visible from both sides light shield means may be provided between the individual supporting units and the reflector elements. For example, the spaces between the individual units may be closed by a flexible flap secured to each supporting unit to extend over the opening between this unit and the next adjacent unit.

In Figures 14 and 15 of the drawings I disclose diagrammatically a sign formed of a series of individual reflector supports rotatably mounted in superimposed relation. Figure 14 discloses a series of laterally spaced reflector supports H, each of which is mounted upon a shaft 92. A series of the reflector supports H are mounted on each shaft 92, one above another. The construction shown in Figures 14 and 15 is identical with the exception that the reflector supports H in Figure 15 are in staggered relationship so that the shafts 92 may be horizontally somewhat closer together than in Figure 14. As a result the reflector elements of Figure 15 are considerably closer together than in Figure 14.

The reflector elements H may be of the type illustrated in Figure 16 of the drawings. This figure illustrates a spherical body 93 having a series of angularly spaced reflecting elements 94 mounted centrally about the same, each reflector 94 being substantially perpendicular to the radius of the sphere. The reflectors 94 are also perpendicular to a plane through the axis of the supporting shaft 92.

A second series of reflector elements 95 are provided above the reflector units 94, as best illustrated in Figure 16, so as to reflect light in an upwardly direction. Similar reflecting surfaces 96 are provided in the lower portion of the spherical body 93 to reflect light in a downwardly direction. Thus the sign illustrated in Figures 14 and 15 will be visible from a level somewhat above the level of the sign, as well as from a level somewhat below the level of the sign. Such a sign would be useful opposite a building where the sign might be viewed from above or below its level, or might well be used on the wall of a hotel lobby, or the like, where it could be viewed from a balcony, as well as from a level below the level of the sign.

The signs shown in Figures 14 and 15 could likewise be made up of the units I, illustrated in Figure 17 of the drawings. This construction has a multi-sided body 98 having a vertical axis. In the construction shown the body 98 is a five sided figure. At the top of the body 98 appears a truncated pyramid 97. A similar truncated pyramid 99 is provided at the lower end of the body 98. The connected bodies 98, 97, and 99 may be rotatably mounted upon a shaft 100. Re-

flector elements 101 are provided in each side of the multi-sided body 98. Similar reflectors 102 and 103 are provided in each side of the truncated pyramid 97 and 99. Thus with this construction, similarly to the construction previously described, the sign may be viewed either from above or below the level of the sign without losing the effect thereof. Similarly the individual supporting units may be arranged to display a plurality of patterns from various levels above the level of the sign, or from a plurality of levels below the level of the sign.

In Figure 18 of the drawings I disclose a sign which is rotatable on a vertical axis and which includes a multiplicity of reflector surfaces throughout the entire circumference thereof. This sign J is arranged for rotation about a vertical shaft 104, although it may, of course, be stationarily mounted for vision by a person walking or otherwise moving around the same. A series of reflector surfaces 105 are provided on the sign surface, each of which are perpendicular to lines of vision 106 from a point 107. A series of reflector surfaces 109 are provided on the cylindrical surface of the sign J, each of which are perpendicular to lines of vision 110 from a point 111. Certain of the reflecting elements 109 are positioned between adjacent reflecting elements 105. An additional series of reflecting surfaces 112 are provided perpendicular to the lines of vision 113 from a point 114. Certain of the reflecting surfaces 112 are positioned between adjacent reflecting surfaces 109. Similarly the entire surface of the sign J may be covered with reflecting elements, alternate reflecting elements of which direct light toward one point of vision, while the remaining reflecting elements direct light toward the second point of vision. Thus as the sign J rotates a constantly changing display is provided to a person viewing the same.

In Figures 19 and 20 of the drawings I disclose a modified form of sign construction which differs somewhat from previously described constructions. In the sign illustrated in Figures 19 and 20 of the drawings a sign board panel 115 is provided having an opening 116 therethrough. A series of pairs of shafts 117 and 119 are mounted in any suitable manner rearwardly of the openings 116. The shafts 117 are positioned relatively near the rear surface of the sign panel 115, while the shafts 119 are spaced rearwardly from the shafts 117. Endless belts or chains 120 are supported by rollers or pulleys 121 and 122 on the shafts 117 and 119, respectively, and by rotation of the shafts the belts may be made to travel endlessly between the pulleys in a manner believed obvious from an examination of Figure 20 of the drawings.

Mounted in spaced relation upon each of the belts 120, I provide reflector elements 123 which are successively displayed through the openings 116 of the sign. The reflector units 123 are preferably supported intermediate their ends to the endless belt 120, in order that the reflector units may maintain proper relationship to the sign opening 116 as they travel over the pulleys or rollers 121. In other words, the reflector units 123 lie flat against the surface of the belts 120 while moving between the pulleys 121 and 122 and maintains substantially right angular relationship to the radius of the pulleys 121 and 122 when traveling over the same. Thus the flat rear surfaces 124 of the reflector units 123 assume substantially vertical position just rearwardly of

the sign panel 115 when in one position of the belts.

Each reflector element 123 is provided with three angularly arranged faces 125, 126, and 127. The reflecting surfaces 126 are clearly visible to a person standing directly in front of the sign and reflect light directly back at a person standing in front of the sign. The reflecting surfaces 125 reflect light back to a person standing angularly to one side of the sign and in front of the same showing a different or separate display from that displayed on the front surfaces 125. The remaining angular surfaces 127 are visible to a person standing in front of the sign and to the other side thereof. Thus three separate displays are visible from different angles with respect to the sign panel 115.

As each of the reflector elements 123 assumes a vertical plane behind the display panel 115 and visible through the opening 116 therein, a different display is created. Thus each of the reflector elements 123 is provided with three separate reflector faces, and as in the form illustrated the belts 120 are each provided with twelve separate reflector elements which successively move into position in front of the sign, the sign is capable of displaying thirty-six different displays, twelve of which are visible from directly in front of the sign and twelve of which are visible from either side of the front of the sign. The belts may travel continuously and without stopping or may move intermittently, the belt stopping which each display element is in position to be viewed through the sign opening 116.

In Figures 21 and 22 I disclose another modified form of construction somewhat similar to that shown in Figures 19 and 20. The sign L is provided with a sign panel 129 having an opening 130 therethrough through which normally vertically mounted belts 131 are visible. As best illustrated in Figure 22 the belts 131 are mounted on transversely extending shafts 132 and 133 and rotate about pulleys 133 and 134 mounted on these shafts, respectively. Reflector elements 135, similar to the reflector elements 123, shown in connection with the sign K are provided on the belts 131. These reflector elements 135 are centrally connected to the belt 131 so that they may travel over the pulleys 133 and 134 without flexing.

A relatively small number of the reflector elements 135 are visible through the opening 130 at a time. A series of successive illustrations may be provided visible through an opening 130 or a continuous sign may be provided, the wording on the sign traveling downwardly or upwardly in order to successively display all of the reflector elements in unison.

It will be seen that with my sign construction a series of illustrations may be provided without moving any of the parts thereof, and similarly a successive series of signs may be displayed visible from different angles or successively brought into view of a person standing in a certain spot. Reflector elements are embodied in the various sign constructions, each element being so constructed as to be substantially directional, so that only one display of the sign may be seen from any point at one time.

In accordance with the patent statutes, I have described the principles of the construction and operation of my sign, and while I have endeavored to set forth the best embodiments thereof, I desire to have it understood that obvious changes may be made within the scope of the following

11

claims without departing from the spirit of my invention.

I claim:

1. A reflector sign including a series of substantially parallel supporting elements, means on said supporting elements for supporting reflector elements substantially on two intersecting planes, each set of reflector elements being arranged into a display and being visible from a point in predetermined angular relation to said supporting elements.

2. A sign comprising a series of spaced substantially parallel supporting elements, a series of reflector elements mounted on said supporting elements to reflect light in one general direction, a second series of reflector elements secured to said supporting elements spaced from said first named reflector elements and in angular relation to said elements of the first named series in a manner to reflect light in a second general direction and substantially angularly spaced from said first named general direction, both of said series of reflector elements being arranged to provide a display.

3. A multi-angular reflector sign comprising a series of spaced multi-angularly surfaced supporting elements, means rotatably supporting said supporting elements on parallel axes, a series of reflector elements secured to one surface of said supporting elements and arranged to reflect light in one direction therefrom, a second series of reflector elements mounted on another surface of said supporting units to reflect light in a second general direction angularly spaced from said first named general direction, and means for rotating said rotatable supporting elements in unison in a single direction.

4. A multi-angular reflector sign comprising a series of supporting elements, a flat surface on one side of said supporting elements, a series of angularly arranged faces on the other side of said supporting elements, the corresponding faces of the supporting elements being in substantial parallel relationship, and reflector elements mounted on each of said angular faces and arranged to reflect light directed against the same, the reflector elements on each of the corresponding angular faces of the sign being visible from a predetermined point with respect to the sign, and the reflector elements of said series of angular faces being arranged to provide a display.

5. A sign comprising a series of supporting elements, means pivotally supporting said elements on parallel axes, each of said supporting elements having a series of angularly spaced surfaces thereupon, reflector elements supported adjacent each of the angularly disposed surfaces of said sign, the reflector elements on the corresponding surfaces of said sign being simultaneously visible from a predetermined point with relation to the sign at substantially right angles to said angularly spaced surfaces, and means for rotating said supporting elements in unison in a single direction.

6. A reflector sign comprising a series of rows of reflector units, each of said rows including a series of independent reflector elements, the reflector elements of alternate rows being generally parallel and arranged to reflect light from a first light source toward a first vision point, said alternate reflector elements being arranged to provide a display at said vision point, said remaining rows of reflector elements being positioned to reflect light from a second light source

12

spaced from the first light source to a second vision point spaced from the first vision point.

7. A reflector sign comprising a series of rows of reflector elements, the reflector elements of each row being generally parallel, certain of said rows being arranged to reflect light from a first light source toward a first vision point, said certain reflector elements being arranged to provide a display at said vision point, the others of said rows of independent reflector elements being mounted in angular relation to said certain rows, said other series of reflector elements being incapable of directly reflecting light from said first light source to said predetermined vision point, said other rows of reflector elements being positioned to reflect light from a second light source spaced from the first light source to a second vision point spaced from the first vision point.

8. A reflector sign comprising a series of rows of reflector elements, the reflector elements of each row being generally parallel, certain of said rows being arranged to reflect light from a first light source toward a first vision point, said certain reflector elements being arranged to provide a display at said vision point, the others of said rows of independent reflector elements being mounted in angular relation to said certain rows, said other series of reflector elements being incapable of directly reflecting light from said first light source to said predetermined vision point, said other rows of reflector elements being positioned to reflect light from a second light source spaced from the first light source to a second vision point spaced from the first vision point, and illuminating means located at said first and second light source.

9. A sign comprising a series of parallel spaced supporting elements, means pivotally mounting said supporting elements along parallel axes, said elements having one surface thereof substantially flat to provide a relatively flat surface for said sign when all of said flat surfaces are turned outwardly, and a series of angularly arranged rows of reflector elements secured to the opposite surface of each of said supporting elements, the reflector elements on one of said rows of reflector elements on each of said supporting elements being visible from one general direction, and the reflector elements of another corresponding row of reflector elements on each supporting element being visible from another general direction at an acute angle to said one general direction.

10. A sign comprising a series of parallel supporting elements, a series of channels secured to said supporting elements, the basis of said channels on each supporting element being arranged on intersecting planes, and a series of reflector elements supported in each of said channels.

11. A sign comprising a series of parallel supporting elements, each of said supporting elements comprising a flat surface on one side thereof and a series of angularly disposed surfaces on the other side thereof, two of said surfaces on said other side being arranged in parallel relationship, and the remaining two surfaces being arranged in angular relationship to said parallel surfaces, reflector elements on the various angularly arranged surfaces, the reflector units of each of said surfaces being arranged to provide a display.

12. A sign comprising a series of supporting elements, a series of rows of reflector elements arranged in angular relationship about the cir-

cumference of said supporting elements, said rows being so positioned that a plurality of rows are simultaneously visible from a single point, each of said reflector elements being arranged to reflect light in a substantially radial direction from each of said supporting units, and the reflector units of corresponding rows of each of said reflector units being arranged to provide a display.

13. A sign comprising a series of supporting elements, means for rotating said elements on a substantially vertical axis, and reflector elements on said supporting elements visible from, and arranged to direct light from a single source toward a plurality of vertically spaced levels.

14. A sign comprising a series of supporting elements, each of said supporting elements being rotatably mounted on a substantially vertical axis, each said supporting element having reflector elements mounted thereon, each of said reflector elements being arranged to reflect light from a light source in a substantially horizontal direction, certain of said reflector elements in each of said supporting elements being arranged to reflect light from said source in a downward direction therefrom, and each said supporting element including reflector elements arranged to reflect light from said source in an upward direction.

15. A sign comprising a rotatable element including a series of reflecting surfaces, a plurality of angularly spaced surfaces being simultaneously visible from a single point, said surfaces being arranged in alternate relationship, alternate of said reflecting elements being arranged substantially perpendicular to a line of vision from one predetermined point, and the intermediate reflector elements being arranged substantially perpendicularly to lines of vision from a second predetermined point.

16. A sign comprising a series of endless belts arranged in parallel relationship, an opening exposing a portion of each of said belts, and re-

flector elements mounted on said belts successively displayed through said opening, the reflector elements being displayed at any time, being arranged to form a display.

5 17. A sign comprising a sign panel, a series of endless belts mounted adjacent said panel, an opening through said panel through which portions of said endless belts are displayed, and a series of multi-angular reflector elements supported in spaced relation on said belts each said element including a plurality of independent angularly spaced reflectors.

10 18. A reflector sign comprising a sign panel, an opening therethrough, a series of endless belts secured adjacent said opening and displayed therethrough, a series of multi-angular reflector elements on each of said endless belts, said belts being arranged to successively display each of said multi-angular reflector elements through said opening and thereby to simultaneously display a predetermined number of said angular reflecting elements through said opening, each said element including a plurality of independent angularly spaced reflectors, the reflector elements of each series being arranged to provide a display.
